PRINTING TELEGRAPH APPARATUS

Albert H. Reiber, Evanston, Ill., assignor to Teletype Corporation, Chicago, Ill., a corporation of Delaware

Application November 14, 1935, Serial No. 49,718

34 Claims. (Cl. 178—35)

The present invention pertains to printing telegraph apparatus and more particularly to recorders responsive to isochronous code signals having a single selective current impulse.

5 The primary object of the invention is to provide a simple start-stop printer having a minimum of operating parts and operative under control of equal length code signals each comprising two elements of opposite signalling conditions 10 whose time intervals are complementary, selective control being manifested by variation in the length of a single line signal impulse in each received code signal.

According to the present invention, the line 15 signal for each character consists of a no-current starting impulse and a current definitive impulse. Specifically, each code signal is composed of two elements, in which each element occurs but once in a code selective signal. In isochronous transmission, the sum of the lengths of the 20 elements in each code signal is equal to unity, and although each element varies in length, nevertheless each element in each code signal is the complement of the other element of that particular 25 code signal. Hence, each signal is formed and each character is determined by the relative lengths of the elements composing the signal.

When the starting impulse is received, a line 30 relay or selector magnet deenergizes and releases its armature, permitting a type wheel to rotate. The type wheel rotates in phase with a transmitting element at the controlling station. During the rotation of the type wheel, the receiving magnet, upon a reversal of signalling conditions 35 which occurs at termination of the starting impulse and the beginning of the contiguous definitive impulse, attracts its armature and causes a printing hammer to operate to print a character. The printing may be accomplished while the type 40 wheel is rotating or the type wheel may through well known type segment aligning means be arrested momentarily while the print hammer is impressed against the type face. The type wheel aligning means may consist, for example, of a 45 jockey or projection on the printing arm which engages with a type aligning toothed wheel to stop the type wheel momentarily, indexing for the proper character at the moment of printing. After printing has been effected, the type wheel is 50 released and continues to rotate and is stopped as it completes one revolution.

The above and other objects of the invention will be apparent from the following description when taken in conjunction with the accompanying drawings, wherein like reference characters

designate similar parts throughout the several views, and in which,

Fig. 10 is a top view of the form of the invention shown in Fig. 9.

Having reference to Fig. 1, there are indicated 25 two monopulse isochronous code signals of the type employed in the selective control of printing apparatus according to the present invention. It is observed that the code signals according to this code are of uniform or equal lengths, that 30 each code signal consists of two elements of opposite polarities or characteristics, and that each monopulse code signal comprises only a starting condition or impulse and a contiguous definitive condition or impulse. The instant at which the 35 reversal of the current or characteristic nature of the impulses occurs is determinative of the identity of the character to be printed and is the instant at which printing is effected. For example, the signal indicated at the left in Fig. 1 is representative of letter "N" and that at the right, of letter "G". A description of the specific embodiments of the invention disclosed in Figs. 2 to 10 will afford a clear understanding of the application of monopulse isochronous code signals to 40 45 printing telegraph receivers.

According to Figs. 2 and 3 a motor 11 and selector electromagnet 12 are mounted upon a base plate 13 and together with the major portion of the apparatus are housed by cover 14 and front 50 plate 15. It is necessary that the speed of motor 11 be regulated so that the type wheel at the receiving station rotate in synchronism and in phase with the transmitting element at the transmitting station. Motor 11 has mounted on its 55

armature shaft 16 a pinion (not shown) which meshes with a gear 17 integral with the collar 18. Gear 17 and collar 18 are mounted for rotation on a shaft 19 journaled in brackets 21 and 22. Also 5 mounted on shaft 19 and having a spline connection with collar 18 is a collar 23 terminating at its forward end in a gear 24. Collars 18 and 23 and their respective gears 17 and 24 rotate continuously upon shaft 19 and impart rotational 10 movement to shaft 19 at predetermined periods through the instrumentality of friction clutch means comprising friction discs 25 and 26 interposed between gears 17 and 24 and a pair of flanged collars 27 and 28 secured to shaft 19. 15 Pressure is exerted by gears 17 and 24 against collars 27 and 28 by virtue of a compression spring 29 restrained between one face of gear 17 and a nut 31 carried on collar 23. The pressure exerted by spring 29 may be adjusted by nut 31 and this 20 adjustment maintained by a lock nut 32. There is inserted between collar 28 and bracket 22 a spacing collar 33.

Secured to shaft 19, adjacent bracket 22 opposite to collar 33 is a drive member 34 (Figs. 3, 4 and 5) comprising an arm 35 disposed between a pair of resilient or spring members 36 and 37. Spring members 36 and 37 are U-shaped, each having one arm thereof riveted to member 34 and the extremity of the other arm disposed laterally as at 38 (Fig. 4) to embrace a stud 39 carried on a star wheel 41. Star wheel 41 is integral with a collar 42 loosely carried on shaft 19 which collar terminates in a type wheel 43. The integral member comprising collar 42 and parts 41 30 and 43 is held loosely upon shaft 19 by shoulder screw 44. Upon initiation of rotation of shaft 19 through its frictional interconnection with gear 17, rotation will be imparted to star wheel 41 and type wheel 43 through the resilient connection between springs 36 and 37 carried on arm 35 and stud 39 carried on star wheel 41.

Arm 35 is fixed upon shaft 19 and springs 36 and 37 are fixed upon the hub-like portion of arm 35, Fig. 5. Body portions of springs 36 and 45 37 are bent into U-shape and are positioned in part by riveting one leg of the spring to the hub portion of arm 35 and in part by pressing the distal end of each spring against the two sides of the arm 35, thus giving to each spring a definite position and definite location when at rest. Pin 39 fixed upon star wheel 41 is positioned 50 between two lateral extensions at the distal ends of the two springs 36 and 37 and the loosely sleeved star wheel 41 is angularly positioned by joint action of the two springs, which act upon the pin 39 to keep it in alignment with the arm 35. Should wheel 41 and pin 39 move out of this 55 determined relative position, one of the springs 36 or 37 will be flexed and will tend to push the pin 39 to bring wheel 41 back into its proper angular position. The functioning of the springs 36 and 37 is as follows: When wedge 83, Fig. 6, is driven by printing arm 63 into a peripheral interstice of star wheel 41, the star wheel will be 60 in motion and may not be in accurate angular position for printing, correction of angular position for printing being effected by wedge 83 when entering an interstice of star wheel 41. Should star wheel 41 be laggard at the printing instant, wedge 83 will advance it and propel it into printing 65 position in advance of the corresponding angular position of shaft 19 and arm 35, thereby moving pin 39 slightly with reference to position of arm 35 and thereby flexing spring 36. On the other hand, should the position of the star wheel 70

41 be in advance of its desired printing position, wedge 83 in entering an interstice will retract wheel 41, thereby flexing spring 37. In either case there will be some slight rotation of shaft 19 during the momentary period of printing when wedge 83 remains within an interstice of star wheel 41, during which momentary period arm 35 will move and pin 39 will be held by wedge 83 and this will cause a displacement of pin 39 with reference to arm 35 and a corresponding flexion of spring 36 or 37 or both. The resilient connection afforded by springs 36 and 37 between star wheel 41 and power driven shaft 19 therefore constitutes a clutch which permits a small correction in angular position of star wheel 41 and printing wheel 43 by control of a minimum molecular mass without the encumbrance of the mass constituted by the shaft 19 and flanged collars 27 and 28 and also free from the driving power of clutch members 25 and 26, a much less powerful drive of spring 36 or 37 being substituted for the full powered drive of clutch discs 25 and 26. Since the function of introducing wedge 83 into peripheral interstice of star wheel 41 is effected by momentum or overthrow of hammer head 32, 25 the reduction of the value of mechanical resistance offered by star wheel 41 and type wheel 43 to the corrective effort of wedge 83 is of importance in performing accurately the quick printing movement of the members of the structure at 30 this instant.

To show more clearly the relations of springs 36 and 37 and pin 39 in Fig. 2, the angle of shaft 19 and therefore of elements 34, 35, and 41 is taken slightly different from the angle of the 35 same elements in Fig. 1.

A shaft 45 is journaled at one end in a bracket 46 and at the other end in plate 15. Carried rotatably on shaft 45 and meshed with gear 24 is a gear 47 provided with a collar 48 having a spline 40 connection with another collar 49 also rotatable and slidably on shaft 45 and provided with an integral disc portion 51. Gear 47 is adapted to be constantly rotated upon shaft 45 through gear 24. The assembly comprising gear 47, collars 48 45 and 49 and disc 51 is adapted to be frictionally connected to shaft 45 through a pair of friction discs 52 and 53 disposed between a flanged collar 54 and ratchet member 55, both fixed to shaft 45 and embracing said assembly. Gear 47 and disc 50 51 are adapted to be pressed against discs 52 and 53 by means of a compression spring 56.

A pawl member 57 of U-shaped conformation to afford a substantial bearing on a stud shaft 59 carried by plate 15 is provided to cooperate 55 with ratchet 55 to control the spacing of printed tape subsequent to the printing operation. Pawl member 57 is normally urged into cooperation with ratchet 55 by means of a spring 61. Pawl member 57 is also provided with a portion 62 which 60 coacts with a printing arm 63 pivotally carried at 64 on a bracket 65. Also carried on pivot 64 is an armature assembly 66 having armature lever 67 cooperating with cores 68 of the selector magnet 12, having a spring 69 with one end connected to armature assembly 66 constantly tending to urge the armature lever 67 counterclockwise against an adjustable stop 71 carried in the bracket 65, and having also an arm 73 which cooperates with a stop latch 74, adjustably positioned for purposes of orientation by means of a slot and screw adjustment 75. Latch arm 74 normally tends to rotate in a counterclockwise direction under the action of a spring 76 into the path of the arm 35. The biasing of arm 74 75

in a counterclockwise direction tends to rotate armature assembly 66 in a clockwise direction, thus assisting the magnetic pull of magnet 12 upon armature 67. 5 The printing arm 63 is provided with a projection 77 to the end of which is connected one end of a spring 78, the other end of which is secured to lever 67. Printing arm 63 normally tends to rotate in a counterclockwise direction about pivot 64, due to the action of spring 78, against an adjustable stop 79 carried on arm 67. The opposite extremity of printing arm 63 is conformed, as shown in Fig. 6, with a laterally disposed portion 81 terminating in a weighted printing hammer 82 which is disposed opposite the type on type wheel 43. Arm 81 is also provided adjacent to hammer 82 with a vertical projection 83 having a wedge shaped top edge which cooperates with the star wheel 41 to arrest momentarily the rotation of the type wheel 43 during the performance of the printing function. A tape 84 is directed between the type wheel 43 and print hammer 82 by mechanism which is well known and hence not shown. Secured to shaft 45 and disposed beneath tape 84 is a tape feed roller 85 and disposed above the tape and cooperating with the tape feed roller 85 to effect the spacing of the tape is a pressure roller 86 which is spring-biased against the tape by a spring (not shown). Positioned above the type wheel is an inking roller 87 (Fig. 2) which is carried by a lever 88 pivotally carried on a stud shaft 89 affixed to plate 15. Inking roller 87 is normally biased into contact with type wheel 43 by a spring 91.

General operation

In the operation of the printer just described, the motor 11 is constantly running through a local source of power in phase with the transmitting apparatus, and gears 17, 24, and 47 are likewise constantly rotating. Shafts 19 and 45 however are restrained from rotation by the coaction of stop arm 35 and latch arm 74, and the coaction of pawl 57 and ratchet 55, respectively. The selector magnet 12, due to the fact that the non-transmitting condition of the line is normally a marking signalling condition, is energized, hence armature assembly 66 is held in its clockwise position, as shown in Fig. 2, and printing lever 63 is held against stop 79 by spring 78.

The operation of the printing apparatus to effect the printing of a character will be initiated by the reception of a starting impulse which is a reversal of the condition prevailing during the stop condition of transmission. In the specific form disclosed, current and no-current operation is presumed, whereupon the reception of a starting impulse of no-current nature will cause the deenergization of the selector magnet 12, the effect of which will be to permit the counterclockwise rotation of armature assembly 66 due to the action of its spring 69. This rotation of assembly 66 will, through its arm 73, cause the clockwise rotation of latch arm 74 a sufficient amount to permit the stop arm 35 to escape its retention by latch arm 74, whereupon type wheel 43 and star wheel 41 will begin to rotate in a clockwise direction (as viewed in Fig. 2) until a reversal of the line signal condition occurs. The character to be printed is determined by the instant in the code signal interval at which a restoration of marking signal occurs. Thus, when the reversal of line condition occurs to determine the character to be printed, the energization of selector magnet 12 will cause an attraction

of assembly 66, the sudden rotation of which is imparted to printing lever 63, which is thereupon thrown against the type wheel to effect printing. The momentum imparted by assembly 66, through adjustable stop 79, to printing lever 63, causes lever 63 to stretch spring 78 so that the actual printing is not performed by pressure applied directly to printing arm 63 by armature lever 67 but rather by the momentum given to lever 63 by armature lever 67 to accomplish what is known as overthrow printing; that is, the printing is actually performed by the overthrow action imparted to hammer head 82 by printing lever 63. As printing lever 63 is thrown against the type wheel, the V-shaped projection 83 is also caused to engage a notch on star wheel 41 identifiable with the character to be printed, thus arresting momentarily the star wheel 41 and consequently type wheel 43 so as to prevent blurred printing.

As the printing lever 63 is actuated sharply in a clockwise direction, this force is imparted also to the pawl 57 through the medium of projection 62. This action upon pawl 57 effects the disengagement of pawl 57 from ratchet 55 which is then permitted to rotate the angular distance corresponding to the pitch of one tooth, the pawl 57 being returned immediately by spring 61. This angular motion of ratchet 55 is transferred to feed roller 85 which in conjunction with pressure roller 86 results in the feeding of the tape a distance of one character space.

After the reception of the stop impulse, the armature assembly 66 is held in its attracted position, thus permitting latching arm 74 to be returned to its counterclockwise position by its spring 76 in position to arrest the movement of arm 35 when the arm 35 has completed one revolution. In this manner the type wheel is stopped in its proper normal position and is rotated through one revolution upon the printing of each character.

Modification

One modified form of the invention is shown in Figs. 7 and 8, and embodies the same principle as the form previously described, the structural adaptations being different. The apparatus for the most part is contained in a housing comprising the cover 101, a base plate 102, and a front plate 103. A synchronous or speed regulated motor 104 is mounted on the base plate 103 and upon its armature shaft 105 is carried a pinion (not shown) which meshes with a gear 106 carried rotatably on a shaft 107, journaled in bearings 108 and 109. The gear 106 is provided with a hub portion 111 which is connected through a tongue and groove connection to the hub 112 of a disc 113. Disc 113 and gear 106, as thus assembled, are frictionally connected to shaft 107 through friction discs 114 and 115 disposed between said assembly and a pair of flanged collars 116 and 117 fixed to the shaft 107. Compressive force is imparted to friction clutch arrangement by means of a compression spring 118 compressed between gear 106 and a nut 119 threaded on hub 112. The pressure of the friction clutch is adjusted by means of nut 119 and the adjustment is maintained by a lock nut 121.

Fixed to the shaft 107 at its forward end is an assembly comprising a notched disc member 70 122, collar member 123, and a type wheel 124. Also fixed to the shaft 107 adjacent to disc 122 is a sleeve 125 provided with a projecting arm 126. Arm 126 cooperates with a shoulder 127 on an armature lever 128 pivoted at 129 to a

bracket 131 carried on frame 132. Lever 128 is provided with an armature 133 which cooperates with the core of a selector electromagnet 134. Armature lever 128 normally tends to rotate in a clockwise direction (as viewed in Fig. 7) in response to the action of a spring 135.

A printing control lever 136 is pivoted at 137 to front plate 103 and is provided with a shoulder 138 which cooperates with a cam roller 139 carried on a stud 151 on disc 122. Lever 136 is provided with an extension 142 which cooperates with a printing lever 143. Lever 143 is provided with a vertical arm 144 terminating in a lateral tip 145 which cooperates with the hooked extremity 146 of armature lever 128. Printing lever 143 is also provided with an arm 147 which terminates in a V-shaped point adapted to cooperate with a series of V-notches formed in the outer periphery of disc 122. Carried on the arm 147 near its extremity is a stud 148 which carries a printing roller 149. Appropriately positioned on printing lever 143 below roller 149 is a stud 151 with which the extension 142 of control lever 136 cooperates. Stud 151 also extends outwardly sufficiently to permit the tape 152 to be directed around it and thence around printing roller 149, as shown in Fig. 7.

Printing lever 143 is also provided with an arm 153 upon which is carried a resilient member 154 which acts as a feed pawl to cooperate with a tape feed ratchet wheel 155 carried on a stud 156 mounted on the front plate 103. Integral with ratchet 155 and also mounted for rotation on stud 156 is a tape feed roller 157, and disposed above the tape feed roller and adapted to coact with the opposite side of the tape is a pressure roller 158 carried on a lever 159 pivoted at 161 to front plate 103. A spring 162 acts to rotate lever 159 in a clockwise direction to impart pressure between rollers 158 and 157. A detent member 163 is mounted upon front plate 103 and appropriately positioned to coact with the teeth on ratchet wheel 155 to prevent back spacing of the tape. There is connected to the vertical arm 144 of the printing lever 143 a printing spring 164, which acts to rotate printing lever 143 so that printing roller 149 will engage a type face on the type wheel 124 and roll therewith to effect printing. The printing mechanism in this form of the invention is electro-mechanically controlled, that is, a latch mechanism normally acting to hold the printing mechanism against operation is controlled by the selector magnet, and when released permits the operation of the printing mechanism by solely mechanical means.

Operation of modified structure

In describing the operation of the structure shown in Figs. 7 and 8 it is assumed that the motor 104 is constantly running and hence gear 106 is rotating continuously on shaft 107 and imparts to said shaft continuously a tendency to rotate through the frictional connection therewith. Shaft 107, however, is prevented from rotating by the cooperation of stop arm 126 with shoulder 127 of armature lever 128, it being understood that the stop condition of the line is marking current and hence selector magnet 134 remains energized. While arm 126 is so arrested, the roller 139 on disc 122 is so positioned as to cooperate with shoulder 138 of control lever 136, which through the cooperation of its extension 142 with stud 151 holds the printing lever 143 in its clockwise position, as shown in Fig. 7.

Upon the reception of a starting impulse, the

selector magnet 134 is deenergized and the armature lever 128 is rotated suddenly in a clockwise direction by its spring 135. The rotation of armature lever 128 effects the disengagement of shoulder 127 from stop arm 126, thus initiating the rotation of disc 122 and type wheel 124. The rotation of armature lever 128, however, is limited by the lateral portion 145 of arm 144, thereby effecting the engagement of portions 145 and 146. As disc 122 begins to rotate, roller 139 becomes disengaged from shoulder 138 and hence printing arm 143 would be free to respond to the action of its spring 164 but for the engagement of portion 145 with end 146 of armature lever 128. The printing mechanism thus is held in a state of suspension until the definitive printing signal is received. As previously described in connection with the first form of the invention, the time at which the reversal of current or signalling condition occurs between the start and stop impulses is determinative of the character to be printed. Therefore, upon the receipt of the stop impulse or at the instant of reversal of current or signalling condition, the selector magnet 134 becomes energized thereby attracting armature lever 128 against the action of its spring 135 and causing the disengagement of extremity 146 from tip 145. Printing arm 143 is thereupon permitted to respond to the action of printing spring 164 which causes printing arm 143 to rotate in a counterclockwise direction (as viewed in Fig. 7). As printing arm 143 begins to rotate, the V-shaped extremity of arm 147 may engage with the periphery of disc 122 and then cooperate with a notch in the periphery of disc 122 corresponding to the character to be printed, the position of said notch with relation to the type faces on the wheel being so related as to properly time the printing operation. Thus in this manner the lever 143 becomes geared to the disc 122 until the point of lever 143 by its arcuate path disengages itself from disc 122, and the speed of movement of the printing lever 143 to print is controlled by the rotational movement of disc 122, and as lever 143 thus rotates with disc 122 in timed relation therewith, the printing roller 149 is caused to roll upon the selected type face of the type wheel 124, the tape 152, of course, being disposed between the printing roller 149 and type wheel 124. No inking arrangement is shown but any suitable form of inking roller or equivalent is intended. As the printing arm 143 is rotated to effect the printing operation, the pawl 154 acts to rotate the feed ratchet wheel 155, and hence the tape feed roller 157, one step or character space. After the printing of the character, the printing arm 143 remains temporarily in its counterclockwise position while the type wheel 124, disc 122, and stop arm 126 continue in their cycle of rotation until stop arm 126 is again arrested by the shoulder 127 of the actuated or attracted armature lever 128. Immediately prior to the termination of the interval of cyclic time whence the stop arm 126 is arrested by shoulder 127, a long low arc 165 in the periphery of disc 122 is presented to the point of arm 147 thus clearing the path for restoration of arm 147, and a typeless arc 166 is presented at the same time to the tape 152, whereupon the roller 139 functions to cam the printing control lever 136 downwardly, and extension 142 acts upon stud 151 to rotate the printing lever 143 clockwise against the action of printing spring 164. In this position or condition the printing arm and armature lever and the members carried on shaft 107 assume

their respective positions indicated in Fig. 7 until the reception of the starting signal of a succeeding character code signal.

Second modification

Another embodiment of the invention is illustrated in Figs. 9 and 10 and embodies a different form of electro-mechanical printing mechanism. In this particular form of the invention, a toggle printing means is employed which is actuated mechanically by a printing spring to effect printing and which is restored mechanically, the selector magnet acting only to control a latching means for the printing mechanism.

Having reference to Figs. 9 and 10, a synchronous or speed regulated motor 171 is mounted on a base plate 172 and carries on its armature shaft 173 a pinion gear (not shown) which meshes with a gear 174 loosely mounted on a shaft 175 journaled at one end in a bracket 176 and at the other end in a front plate 177. Gear 174 is frictionally connected to shaft 175 by means of a friction clutch comprising a pair of discs 178 and 179 of friction material, a pair of flanged collars 181 and 182, and a compression spring 183. Fixed to the forward end of shaft 175 are a type wheel 184, a star wheel 185, and a stop disc 186. A gear 187 is also fixed to shaft 175 and meshes with a gear 188 fixed to a collar 191 mounted on a shaft 189 journaled in a bracket 192 and front plate 177. Also integral to collar 191 is a disc 193 provided with spaced studs 190, which act to restore the toggle printing mechanism to its latched position shown in Fig. 9.

A selector electromagnet 194 is mounted on a bracket 195 fixed to the front plate 177 and controls an armature assembly 200 in the form of a bell crank pivoted at 196 and having one arm 197 carrying an armature 198 cooperating with the core of the selector magnet 194. The other arm 199 of assembly 200 coacts with a projection 201 on disc 186 to hold shaft 175 against rotation. Arm 197 terminates in a laterally disposed portion 202 which cooperates with an escapement assembly comprising a lug 235 on a toggle link 206 and a hook end of a latch member 203 pivotally carried at 204 on arm 205 of link 206 of the toggle printing mechanism comprising a toggle lever 207 pivoted at 208 to a bracket 209 mounted on the front plate 177. Link 206 is also pivoted upon a printing arm 211 pivoted at 212. Printing arm 211 is provided with a laterally disposed platen portion 213 which coacts with the type wheel 184, and a vertical projection 214 which coacts with the star wheel 185 to index for the proper character to be printed.

Link 206 and toggle lever 207 are pivotally articulated at 215, on which pivot is also carried one end of a restoring member 216, the other end of which is provided with a slot cooperating with a stud 217 mounted on front plate 177. Each stud 190 mounted on the face of disc 193 coacts with an offset portion 222 (Fig. 10) on link 216 to effect the restoration of the toggle printing mechanism and the latch 203 to their positions shown in Fig. 9.

The tape feeding mechanism comprises a cam 223 fixed to shaft 175 which cooperates with one arm of a bell crank lever 224 pivoted at 225 to front plate 177 (Fig. 9). At the extremity of the other arm of bell crank 224 is pivoted a pawl 226 which coacts with a tape feed ratchet wheel 227. Bell crank 224 is acted upon by a spring 228 and pawl 226 is biased into engaging relation with ratchet wheel 227 by a spring 229. Thus,

when bell crank 224 rides off of the high portion of cam 223, spring 228 acts to rotate bell crank 224 quickly in a clockwise direction to advance ratchet wheel 227 one angular step. A spring actuated detent pawl 231 holds ratchet wheel 227 against slipping backward. Fixed to the outer end of shaft 219 is a tape feed roller 232, and cooperating with roller 232 is a spring actuated pressure roller 233.

Operation of modified structure

In operation, the motor 171 is running continuously through a local source of power in phase with the transmitting apparatus, thereby imparting constant rotation to gear 174. Shafts 175 and 15 189 are restrained against rotation by the engagement of stop lug 201 with arm 199 of bell crank 200, due to the energization of selector magnet 194. The toggle printing mechanism is latched preparatory to effecting printing by engagement of latch 203 with arm 197 of assembly 200. At the commencement of the starting impulse, the selector magnet 194 becomes deenergized, thereupon permitting assembly 200 to respond to its spring 234 to cause the disengagement of arm 199 from stop lug 201 to initiate the rotation of shaft 175, and to effect simultaneously the disengagement of arm 197 from latch 203. Lateral portion 202 of arm 197 upon riding off of latch 203 engages a lug 235 on toggle link 206 due 30 to the stepped relation between lug 235 and the hook shoulder on latch 203. Shaft 175 upon rotation also effects the rotation of shaft 189 through gears 187 and 188, which in the embodiment shown permit one-fourth revolution of shaft 189 35 for each complete revolution of shaft 175.

At the instant of reversal of the signalling condition, which is the point at which printing is effected and is determinative of the character to be printed, the selector magnet 194 again becomes 40 energized and rotates assembly 200 in a counter-clockwise direction against the action of spring 234 to return arm 199 into the path of stop lug 201, and also to disengage portion 202 of arm 197 from lug 235 and thus from toggle link 206. 45 Portion 202 on becoming disengaged from lug 235 escapes latch 203, thus permitting the toggle printing mechanism to respond to the action of a printing spring 236, thereby bringing toggle lever 207 against limiting stop 237 of a pair of limiting 50 stops 237 and 238. In the course of the movement of the toggle printing mechanism the platen 213 is raised against type wheel 184 to effect printing upon a tape 239 and then is lowered to permit the continued rotation of type wheel 184 and 55 shaft 175. During the printing movement of printing arm 211, projection 214 coacts with a notch in star wheel 185 to arrest the type wheel 184 momentarily while printing is effected.

When the toggle printing mechanism responds 60 to the action of spring 236, the member 216 is also carried toward the left (as viewed in Fig. 9) to bring the offset portion 222 thereof into position preparatory to effect the restoration or return of the toggle printing mechanism to its position shown in Fig. 9 through the coaction of a lug 190 and shoulder 222 which occurs near the end of the cycle of rotation of disc 186, and therefore of shaft 175. When this happens, lug 190 carries member 216 rightwardly until latch 70 203 reengages portion 202 on arm 197, and then lug 190 slips off of shoulder 222 after having completed the restoration function and stops at the position indicated in Fig. 9. In progress of resetting of toggle members 206 and 207, the stabber 75

214 and the platen 213 are operated into and then out of their printing positions, but during that operating condition, a toothless arc 218 is presented to the stabber 214 by the star wheel 185 so that the star wheel is not stopped, and a typeless arc (not shown) is presented to the tape 239 and to platen 213 by type wheel 184, so that the tape, though moved toward the type wheel, is not marked.

10 As the shaft 175 rotates, like motion is also imparted to tape feed cam 223 which rotates tape feed bell crank lever 224 in a counterclockwise direction to store up energy in spring 228, so that immediately prior to the arrestment of 15 lug 201 by arm 199, lever 224 will drop off the high part of cam 223 and respond to the pull of spring 228 to actuate through pawl 226 the tape feed ratchet 227 and effect through rollers 232 and 234 the spacing of the tape.

20 Although the present invention has been disclosed in connection with certain specific embodiments thereof, it is understood that such embodiments are merely illustrative and not restrictive and that all forms coming within the scope of 25 equivalency of the appended claims are intended to be covered by the invention.

What is claimed is:

30 1. In a printing telegraph receiver, a start-stop shaft, a normally energized magnet, a printing means, means responsive to the deenergization of said magnet for releasing said shaft for rotation, and means effective upon the reenergization of said magnet for controlling the operation of said printing means.

35 2. In a printing telegraph receiver, a single magnet responsive to monopulse isochronous code signals comprising two elements in which each element occurs but once in a code signal, each element in the code signal being the chronological 40 complement of the other element, printing means, and means responsive to said magnet on the transition from one to the other of said elements to effect the operation of said printing means.

45 3. In a printing telegraph receiver, a single magnet responsive to equal length code signals comprising two complementary elements of different nature, a printing means, means effective upon the receipt of one of said elements for preparing said means for action, and means effective 50 upon the transition from said one to the other of said elements to consummate the action of said printing means.

55 4. In a printing telegraph receiver, a start-stop shaft, printing means, a single magnet responsive to equal length code signals comprising two complementary elements of different nature, means effective upon the receipt of one of said elements for initiating the rotation of said shaft, and means effective upon the transition from one 60 to the other of said elements to effect initially the operation of said printing means and subsequently the arrestment of said shaft.

65 5. In a printing telegraph receiver, a single magnet responsive to equal length code signals, each signal comprising a first condition and a second condition of complementary periodic lengths, printing means, and means responsive to said magnet on the transition from said first to said second condition to effect the operation of 70 said printing means.

75 6. In a printing telegraph receiver, a start-stop shaft, printing means, a single magnet responsive to equal length code signals, each signal comprising a start condition and a stop condition of complementary periodic lengths, means respon-

sive to the start condition of a signal for initiating the rotation of said shaft, and means responsive to said magnet on the transition from start to stop condition to effect the operation of said printing means.

5 7. In a printing telegraph receiver, a start-stop shaft, printing means, a single magnet responsive to equal length code signals, each signal comprising a start condition and a stop condition of complementary periodic lengths, means responsive to the start condition of a signal for initiating the rotation of said shaft, and means responsive to the transition from start to stop condition to effect initially the operation of said printing means and subsequently the arrestment 15 of said shaft.

8. In a printing telegraph receiver, a single magnet responsive to equal length code signals, each signal comprising a first condition and a second condition of complementary periodic lengths, printing means, spacing means, and single means responsive to the transition from said first to said second condition to effect simultaneously the operation of both of said means.

20 9. In a recorder, a start-stop shaft, recording means, a single magnet responsive to equal length code signals, each signal comprising a first condition and a second condition of complementary periodic lengths, means comprising a first element and a second element resiliently connected to 30 each other, means responsive to said first condition to cause said first element to initiate the rotation of said shaft, and means responsive to the transition from said first to said second condition to effect, through said elements, initially the operation of said recording means and subsequently the arrestment of said shaft.

35 10. In a recorder, a single magnet responsive to equal length code signals, each signal comprising a first condition and a second condition of complementary periodic lengths, recording means, indexing means for said recording means, means responsive to said first condition for preparing said recording means for action, and means effective upon the transition from said first to said 40 second condition to release said recording means for action under the control of said indexing means.

45 11. In a recorder, a single magnet responsive to equal length code signals, each signal comprising a first condition and a second condition of complementary periodic lengths, means controlled by said magnet, recording means provided with a latch means having a first component and a second component adapted to be controlled by 50 said magnet-controlled means, and means responsive to said first condition to render said magnet-controlled means cooperable with said first component to prepare said recording means for action, said magnet-controlled means operable in response to the transition from said first to said second condition to overcome the influence 55 of said last recited means to cause the disengagement of said first component from said magnet-controlled means, and to escape said second component to release said recording means for action.

60 12. In a recorder, a single magnet responsive to equal length code signals, each signal comprising a first condition and a second condition of complementary periodic lengths, means controlled by said magnet, recording means provided with a double trip-off latch adapted to be controlled by said magnet-controlled means, means responsive to said first condition to render said magnet-controlled means cooperable with said 70 75

latch to prepare said recording means for action, and means operative pursuant to the effect of the transition from said first and said second condition on said magnet-controlled means to establish, through the cooperable relationship between said magnet-controlled means and said latch, the effectiveness of said recording means.

13. In a printing telegraph receiver, a single magnet responsive to equal length code signals, each signal comprising a first condition and a second condition of complementary periodic lengths, printing means, a start-stop shaft, control means for said shaft, means effective in response to the first condition for actuating said printing means to establish a first predetermined condition in said control means, and means effective upon the transition from said first to said second condition to establish through said printing means a second predetermined condition in said control means.

14. In a printing telegraph receiver, a single magnet responsive to equal length code signals, each signal comprising a first condition and a second condition of complementary periodic lengths, printing means, spacing means, a start-stop shaft, control means for said shaft, means effective in response to the first condition for actuating said printing means to establish a first predetermined condition in said control means, and means effective upon the transition from said first to said second condition to establish through said printing means a second predetermined condition in said control means and to effect simultaneously the operation of said spacing means.

15. In a recorder, a start-stop shaft, printing means, a single magnet responsive to electrical signalling conditions for controlling said printing means, and means controlled by said printing means for controlling said shaft.

16. In a printing telegraph receiver, a start-stop shaft, a type wheel carried on said shaft, means responsive to the first portion of a received signal for starting said shaft, and means responsive to the second portion of said received signal for printing a selected character from said type wheel.

17. In a printing telegraph receiver, a start-stop shaft having a normal position of arrest, a type wheel carried on said shaft, means responsive to the first portion of a received signal for starting said shaft, and means responsive to the second portion of said received signal for printing from said type wheel while said shaft is out of its normal position.

18. In a printing telegraph receiver, a start-stop shaft, means responsive to the first portion of a received signal for starting said shaft and responsive to the second portion of said received signal for restoring stop conditions for said shaft, and printing means responsive to said second portion of said received signal through operation of said first means.

19. In a printing telegraph receiver, a start-stop shaft, means responsive to the first portion of a received signal for starting said shaft and responsive to the second portion of said received signal for restoring stop conditions for said shaft, a type wheel on said shaft, and a printing hammer operable by said first means in response to said second portion of said received signal.

20. In a printing telegraph receiver, a start-stop shaft, means responsive to a first received signal for starting said shaft and responsive to a second received signal for restoring stop conditions for said shaft, a type wheel on said shaft, a

spring-propelled printing hammer, a cam on said shaft for setting said hammer into its spring tensioned position, and a latch for said hammer operable to unlatch said hammer in response to said second signal through operation of said first means.

21. In a printing telegraph receiver, a start-stop shaft, means responsive to a first received signal for starting said shaft and responsive to a second received signal for restoring stop conditions for said shaft, type wheel on said shaft, a spring-propelled printing hammer, a cam driven by said shaft for setting said hammer into its spring tensioned position, and a latch for said hammer operable to unlatch said hammer in response to said second signal through operation of said first means.

22. In a printing telegraph receiver, a start-stop shaft, a printing wheel on said shaft, printing means for printing from said wheel while said shaft is in motion, means for stopping said wheel momentarily during printing, and a resilient connection between said shaft and said wheel permitting stopping of said wheel while said shaft is in motion.

23. In a printing telegraph receiver, a start-stop shaft, a printing wheel on said shaft, printing means for printing from said wheel while said shaft is in motion, and clutch means between said wheel and said shaft for enabling the stopping of said wheel for printing while said shaft is in motion.

24. In a printing telegraph receiver, a start-stop member, a printing wheel rotatable by said member, printing means for printing from said wheel while said start-stop member is in motion, means for stopping said wheel momentarily during printing, and a resilient connection between said start-stop member and said wheel permitting stopping of said wheel while said start-stop member is in motion.

25. In a printing telegraph receiver, printing means comprising a single magnet responsive to two line signals to print a character, a start-stop shaft, control means for said shaft, means controlled by the operation of said printing means in response to a first signal to establish a first control condition in said control means, and means controlled by the operation of said printing means in response to a second signal to establish a second control condition in said control means.

26. In a printing telegraph receiver, printing means comprising a single magnet responsive to equal length code signals, each signal comprising a first condition and a second condition of complementary periodic lengths, a start-stop shaft, control means for said shaft, an assembly comprising a first part and a second part resiliently interconnected, means effective in response to the first condition to establish through said first part a first predetermined condition in said control means and to prepare through said second part the printing means for action, and means effective upon the transition from said first to said second condition to establish through said first part a second predetermined condition in said control means and to effect through said second part the printing operation.

27. In a printing telegraph receiver, a shaft, a magnet, mechanically compelled printing means, and means controlled by said magnet for releasing said shaft for rotation and simultaneously preparing said printing means for effective operation and subsequently effective under control of said magnet for compelling the opera-

tion of said printing means to consummate the printing function.

28. In a printing telegraph receiver, a start-stop shaft, a normally energized magnet, mechanically compelled printing means, means responsive to the deenergization of said magnet for releasing said shaft for rotation, and means effective upon the reenergization of said magnet for compelling the operation of said printing means.
- 10 29. In a printing telegraph receiver, a single magnet responsive to equal length code signals comprising two complementary elements of different nature, mechanically compelling printing means, means effective upon the receipt of one of said elements for preparing said means for action, and means effective upon the transition from one to the other of said elements to compel the consummate action of said printing means.
- 20 30. In a printing telegraph receiver, a single magnet responsive to equal length code signals, each signal comprising a first condition and a second condition of complementary periodic lengths, mechanically compelled printing means, and means responsive to the transition from said first to said second condition to compel the operation of said printing means.
- 25 31. In a recorder, a start-stop shaft, printing means, a single magnet responsive to received signaling conditions for controlling said printing means, means controlled by said printing means for controlling said shaft, and means for effecting the adjustment of said last recited means to se-

cure the proper orientation of said shaft with the received signaling conditions.

32. In a printing telegraph receiver, printing means comprising a single magnet responsive to two line signals to print a character, a start-stop shaft, control means for said shaft, means controlled by the operation of said printing means in response to a first signal to establish a first control condition in said control means, means controlled by the operation of said printing means in response to a second signal to establish a second control condition in said control means, and means for effecting the adjustment of said control means to secure the proper orientation of said shaft with said line signals.

15 33. In a printing telegraph receiver, printing means operable through successive selective positions, a signal receiving magnet and armature, means responsive to one movement of said armature to initiate operation of said printing means, and means responsive to a reverse movement of said armature to control said printing means to print.

20 34. In a printing telegraph receiver, printing means operable at uniform speed through successive selective positions, a signal receiving magnet and armature, means responsive to one movement of said armature to initiate operation of said printing means, and means responsive to a reverse movement of said armature to control said printing means to print.

25 ALBERT H. REIBER.
